by Ralph Taish ATTORNEY.

UNITED STATES PATENT OFFICE.

JOHN S. ELLIS, OF ST. LOUIS, MISSOURI.

DESIGN FOR A SCRAPER.

54,311.

Specification for Design.

Patented Dec. 23, 1919.

Application filed October 22, 1918. Serial No. 259,283. Term of patent 14 years.

To all whom it may concern:

Be it known that I, JOHN S. ELLIS, a citizen of the United States, residing at the city of St. Louis, State of Missouri, have invented a new, original, and ornamental Design for Scrapers, of which the following is a specification, reference being had to the accompanying drawing, forming a part thereof.

The drawing illustrates a scraper embodying my new design, Figure 1 being a perspective view, Fig. 2 being a plan view, and Fig. 3 being an edge view.

My new design for scrapers comprises a flat base or body-portion A for the most

part substantially circular in plan view. Rising obliquely from base or body-portion A, is a plain, flat lateral finger-grip extension B gently rounded at its outer edge. Base A substantially throughout its area has a multitude of relatively small substantially circular and spaced apertures or perforations a and, on its under face, has a multitude of rough protuberances a' appearing as a series of spaced closely nested or clustered teeth or spurs.

I claim:

The ornamental design for a scraper substantially as shown and described.

JOHN S. ELLIS.
